[57] CLAIM

The ornamental design for a window shelf, as shown
and described.

DESCRIPTION

FIG. 1 is a top, front, and right side perspective view of
a window shelf showing my new design;
FIG. 2 is a front elevational view thereof;
FIG. 3 is a rear elevational view thereof;
FIG. 4 is a reduced top plan view thereof;
FIG. 5 is a reduced bottom plan view thereof; and
FIG. 6 is a right side elevational view thereof, the left
side being a mirror image of that shown.
